LOCK MECHANISM

Filed Dec. 10, 1931

UNITED STATES PATENT OFFICE

HARRY G. KIEHL, OF READING, PENNSYLVANIA, ASSIGNOR TO READING HARDWARE CORPORATION, OF READING, PENNSYLVANIA, A CORPORATION

LOCK MECHANISM

Application filed December 10, 1931. Serial No. 580,175.

This invention relates to improvements in lock mechanisms.

The primary object of this invention is the provision of an improved lock mechanism which will operate efficiently at all times independent of the actual position of the dead bolt. It frequently happens in lock mechanisms that the dead bolt is only partially extended into its keeper by actuation of the turn knob on the inside of the closure. Under such circumstances with some types of lock mechanisms, it is impossible to key actuate the dead bolt into fully retracted position. With the present mechanism it is possible for the operator using a key in the outside of the lock, to fully retract the dead bolt, without being aware that the same was not entirely thrown into fully extended position, merely with a natural bolt retracting turn of the key.

While I clearly understand that it is old to associate levers and the like directly upon the dead bolt, which will enable an operator to fully retract the dead bolt from partially extended position by means of the key controlled cam, such as shown in U. S. Patents Nos. 892,347 and 1,678,994, merely by a natural bolt retracting turn of the key controlled cam, and further that by reverse rotation of the key controlled cam of the lock mechanism it is possible to retract the dead bolt fully from a partially extended position, such as shown in U. S. Patent 1,099,105, yet the present invention relates to means for more naturally accomplishing the desired result by the use of mechanism in which the parts are assembled in a relatively simple and sturdy association.

Other objects and advantages of this invention will be apparent during the course of the following detailed description.

In the accompanying drawing, forming a part of this specification, and wherein similar reference characters designate corresponding parts throughout the several views,

Figure 1 is a fragmentary view showing the details of the improved lock mechanism, with the dead bolt retracted.

Figure 2 is a view of the parts shown in

Figure 1, with the dead bolt partially extended.

Figure 3 is a view showing the lock details with the dead bolt fully extended.

Figure 4 is a fragmentary view showing the improved association of a cam controlled lever, with a cam action upon the dead bolt construction.

Figures 5, 6 and 7 are fragmentary sectional views taken substantially on their respective lines in Figure 1 of the drawing.

In the drawing, wherein for the purpose of illustration is shown only a preferred embodiment of the invention, the letter A may generally designate a lock mechanism, which may include a case B of any approved nature having the improved dead bolt mechanism C associated therewith. A pin tumbler lock or other means D is mounted upon the case B for actuating the tumbler mechanism E and the retraction and projection of the dead bolt construction C, and for performing other functions commonly understood in this art.

The lock case B may include a face plate 10, opposite side walls 15 and 16, and marginal boundary walls 17, which in the illustration are rigidly affixed with the side wall 15, the latter having tapped lugs 19 for receiving screws 20^a by means of which to attach the wall 16 in place. The design and structural features of the case B may vary widely.

The lock bolt mechanism C is more particularly of the type described in a co-pending application, Serial No. 561,053, filed September 3, 1931, in that the same includes a reciprocating frame 20 mounted in the lock case which rotatably supports the cylindrical dead lock bolts 21 and 22. The frame 20 is assisted in its guided movement by means of a lug 24 which slides along a horizontal groove 25 provided in the wall 15 of the lock case B, as shown in Figure 7.

Any approved type of cam operating mechanism may be provided for actuating the tumbler E and bolt features of the lock. In the preferred instance an adjustable pin tumbler type of lock cylinder 27^a is used which is provided with a substantially Y-shaped or bifurcated bolt actuating cam arm or roll back 27. The latter provides the bit

portions 28 and 29 which extend in relative divergence with respect to the axis of rotation of the cam arm.

The tumbler E is of the reciprocatory type including a body portion which is mounted directly upon the back of the dead bolt frame 20, as shown in Figure 4. Its upper arm is provided with a pair of parallel extensions or lugs 33 and 34 which slidably extend into the open spaces 35 and 36 respectively on the upper arm 38 of the dead bolt frame or shank 20. The lower arm of the tumbler body 30 is provided with an extension 39 which slides in an upwardly opening slot 40 on the lower arm 41 of the dead bolt frame 20, as shown in Figure 1. This extension 39 terminates in a cylindrical shaped stud 42, against which the cam arms 44 of the thumb turn piece 45 operate, in order to actuate the tumbler E and the dead bolt mechanism C from the inside of the closure on which the lock mechanism is mounted, as will be well understood by those skilled in the art relating to this invention. The tumbler E is provided with a rigid guide rod or finger 46 upon which a spiral spring 47 is mounted; the latter being compressed against an apertured lug 48 on the rear of the dead bolt frame 20, in which the free end of the finger 46 seats. This compression of the spring 47 normally urges the tumbler E in the direction of the cam arm 27.

A latch bolt is of course provided in connection with the lock mechanism A, but is not shown in the drawing. It is actuated, as in conventional practice, by means of a latch bolt operating lever 50 which is pivoted at 51 directly upon the dead bolt frame 20. A lever 52 is also pivoted at 53 on the dead bolt frame 20, as shown in Figure 1, in position to be actuated by the cam arm 27 after the dead bolt mechanism has been fully retracted, for the obvious purpose of retracting the latch bolt.

During normal operation, a key inserted into the pin tumbler cylinder 27^a will permit actuation of the cam arm 27, in well known manner, and to effect a projection of the dead bolts 21 and 22 it is merely necessary to turn the key in the natural direction, which feeds the bit ends 28 and 29 of the cam arm 27 into the recesses 35 and 36 of the dead bolt frame 20. They engage the extensions 33 and 34 of the tumbler E, depressing the latter so as to remove them from engagement with the fixed fence or stump 55, which is best shown in Figure 2 of the drawing. Engagement of the bit arms in the recesses 35 and 36 then permits movement of the frame 20 for projecting the dead bolts 21 and 22 into their keepers, and as the cam arm 27 is moved to throw the dead bolts to their fully projected positions the tumbler E springs into position with the extensions 33 and 34 in engagement at opposite sides of the fixed fence or stump 56, shown in Figure 2, which locks the dead

bolts in their projected positions against unauthorized retraction.

A thumb turn handle is of course provided, which fits into the hub of the thumb turn piece 45 above described, permitting the tumbler E to be depressed, and by reason of engagement of the thumb turn piece arm 44 at opposite sides of an extension 60 on the frame 20, the latter and its dead bolts 21 and 22 therewith may be extended or retracted at will, from the inside of the closure on which the lock mechanism is placed.

If the dead bolt is not fully extended, as will sometimes happen, particularly when the same is actuated upon the inside of the closure on which the lock mechanism is positioned, thru the thumb turn handle, it is readily apparent that the bit ends of the cam arm 27 will not properly enter the recesses 35 and 36 of the frame 20 for actuating the tumbler mechanism. In order to compensate for such condition, so that involuntarily the person actuating the dead bolt by means of a key will, by a natural retractive turn of the key, cause the proper synchronizing of the bit ends of the cam arm 27 with the frame and tumbler details, I have provided a spring actuated lever 70, which is pivoted at 71 directly upon the case B. This lever 70 at its free end is provided with one arm portion 72, in position to engage a sloping surface 75 upon the rear surface of the frame 20. This surface 75, as shown in Figure 4 of the drawing, and elsewhere, is positioned at an acute angle with respect to the line of travel of the dead bolt mechanism. The spring 77 normally engages the lever 70 to force the arm 72 into a cam engagement with the surface 75, as shown in the drawing. The lever 70 also has another arm extension 79 which is normally out of the path of travel of the bit ends of the cam arm 27 as the dead bolts 21 and 22 are fully projected and fully retracted.

However, in event the dead bolt is only partially projected, as shown in Figure 2 of the drawing, the spring actuated lever 70 will be positioned so that the arm portion 79 thereof lies in the path of travel of the free end of the cam arm 27. Under these conditions, a person desiring to unlock the mechanism will insert a key, and turning the cylinder for a dead bolt retracting operation will cause the bit end 29 of the cam arm 27 to come into engagement with the arm portion 79 of the lever 70. The actuating force will push the lever 70, at the arm 72, against the cam surface 75 of the dead bolt frame 20 in order to complete the projection of the dead bolts 21 and 22, and as the cam arm 27 is turned for a normal dead bolt retracting operation the same will actuate the tumbler E and cause a complete retraction of the dead bolt mechanism in a manner which is perfectly obvious from the above description in connection with the illustration.

Various changes in the shape, size, and arrangement of parts may be made to the form of invention herein shown and described, without departing from the spirit 5 of the invention or the scope of the claims.

I claim:

1. In a lock mechanism the combination 10 of a case, a bolt slidably mounted upon the case, a cam for direct projecting and retracting actuation of the bolt, and a member movably mounted in the case independently of the bolt and in position to be engaged by the cam when the bolt is in partial locking extension and moved by further actuation of the 15 cam into engagement with the bolt for moving the latter into full locking extension.

2. In a lock mechanism the combination 20 of a case, a slideable bolt mechanism upon the case, tumbler mechanism operatively associated upon the case with the bolt mechanism, cam means for actuating the tumbler mechanism and bolt mechanism for retracting and projecting the latter with respect to the case, a spring actuated lever pivoted on a fixed 25 axis on the case and spring urged into engagement with the bolt mechanism, said lever being positioned out of the path of movement of the cam arm when the bolt mechanism is either fully projected or fully retracted and in position to be engaged by the cam arm when the bolt is only partially projected so that during a normal bolt retracting movement the cam arm will engage the lever and move it against the bolt mechanism 30 and force the bolt mechanism into a fully projected position with respect to the case.

3. In a lock mechanism the combination 35 of a case, a slideable dead bolt construction having a cam face thereon at an acute angle with respect to the line of travel of the bolt construction, a spring urged lever pivoted on the case having an end urged into engagement with the said cam face of the dead bolt mechanism, a cam arm for actuating the 40 dead bolt construction, said lever having a portion thereof positioned in the path of travel of the cam arm only when the dead bolt is partially projected so that during a normal bolt retracting actuation of the cam 45 arm the lever will be actuated thereby against said bolt construction for causing a projection thereof.

4. In a lock construction the combination 50 of a case, a bolt construction slidable on the case, a tumbler mechanism associated with the case and with the bolt construction, a key actuated cam arm on the case for actuating the tumbler mechanism and bolt construction for fully projecting and fully retracting the 55 latter, a member pivoted on a fixed axis on the case, a spring urging the said member into cam engagement with the bolt construction, said member having a portion thereon positioned in the path of travel of the key 60 actuated cam arm only when the bolt is par-

tially projected so that during a normal bolt retracting turn of the cam arm the latter will engage the lever and force it against said bolt construction for throwing the latter into fully projected position.

70

5. In a lock mechanism the combination 75 of a case, a dead bolt construction movably mounted in the case, a movable tumbler mechanism associated with the case and dead bolt construction, a key actuated cam arm, said bolt construction and tumbler mechanism having only rigid projections thereon for cooperation with the cam arm to cause full projection and full retraction of the bolt construction, and auxiliary means engageably associated with the bolt construction and mounted in the case for movement relative to the bolt so as to be positioned in the path of movement of the cam arm when the bolt construction is partially projected whereby during a normal bolt retraction turn of the cam arm the latter will engage the said auxiliary means for forcing the bolt construction into a fully projected position.

80

6. In a lock mechanism, the combination 85 of a case, a bolt movably mounted upon the case, a cam for projecting and retracting the bolt, a member movably mounted upon the case independently with respect to the bolt and having interengagement with the bolt so as to be movable therewith into the advanced path of movement of said cam when the bolt is merely in partial locking extension so that during a normal bolt retracting movement the cam will first engage the member and move it and the bolt therewith to project the bolt into locking extension and thereafter the cam will ride off the member and move the bolt into retracted position.

90

7. In a lock mechanism, the combination 95 of a case, a bolt movably mounted upon the case, a cam for projecting and retracting the bolt, a member movably mounted upon the case independently with respect to the bolt and having interengagement with the bolt so as to be movable therewith into the advanced path of movement of said cam when the bolt is merely in partial locking extension so that during a normal bolt retracting movement the cam will first engage the member and move it and the bolt therewith to project the bolt into locking extension and thereafter the cam will ride off the member and move the bolt into retracted position, said member being positioned out of the path of movement of the cam when the bolt is either fully projected or fully retracted.

100

8. In a lock mechanism, the combination 105 of a case, a bolt movably mounted upon the case, a cam for projecting and retracting the bolt, and corrective means movably mounted in the case independently with respect to the bolt and cooperatively engageable by the cam when the bolt is in merely partial locking ex-

110

115

120

125

130

tension to project the bolt into full locking extension during the initial part of a bolt retracting movement of the cam.

9. In a lock mechanism, the combination of a case, a bolt movably mounted upon the case, a cam for projecting and retracting the bolt, and corrective means movably mounted in the case independently with respect to the bolt and cooperatively engageable by the cam :10 when the bolt is in merely partial locking extension to project the bolt into full locking extension during the initial part of a bolt retracting movement of the cam, said means being positioned out of the path of movement :15 of the cam when the bolt is either fully projected or fully retracted.

10. In a lock mechanism, the combination of a case, a bolt movably mounted upon the case, a cam for projecting and retracting the :20 bolt, a lever device pivoted upon the case and being associated with the bolt for movement therewith so as to be positioned in the path of the cam movement during a bolt retracting movement of the latter when the bolt is :25 merely partially projected, whereby the cam will engage the lever device and move it and the bolt therewith to project the bolt into full locking extension.

11. In a lock mechanism, the combination of a case, a bolt movably mounted upon the case, a cam for projecting and retracting the bolt, a lever device pivoted upon the case and being associated with the bolt for movement therewith so as to be positioned in the path :30 of the cam movement during a bolt retracting movement of the latter when the bolt is merely partially projected, whereby the cam will engage the lever device and move it and the bolt therewith to correct the position of the :35 bolt, said lever device being positioned out of the path of movement of the cam when the bolt is fully projected and when it is fully retracted.
